UNITED STATES PATENT OFFICE

ARTHUR F. O'CONNOR, OF CHICAGO, ILLINOIS

HAND BRAKE

Application filed June 24, 1929. Serial No. 373,205.

This invention relates to hand brakes.

An object of the invention is to provide a brake mechanism of the pull-up type, including a winding device upon the end wall of a car, and flexible means extending from the winding device underneath the car to be connected with the brake shoes, in conjunction with a mechanism at the lower corner of the car, adapted to cooperate with the flexible means in such manner as to transmit the actuating force applied thereto in a highly efficient manner.

A further object of the invention is to provide a brake mechanism of the character indicated, including a pivotally mounted device positioned substantially at the point of change in direction from horizontal to vertical of the flexible means, and wherein said device automatically adjusts itself to variations in the position of the brake chain and prevents displacement of the device with reference to its normal efficient operating position.

Still another object of the invention is to provide a pivotally mounted device of the character indicated, so constructed as to engage the flexible means only after the same have tightened somewhat, thereby permitting initial relative movement of the loose flexible means with reference to the device, and afterwards bringing about movement of the device in unison with the flexible means.

A still further object of the invention is to provide a device of the character referred to, wherein means are provided to permit relative movement of the flexible means with reference to the device after the same has reached the limit of its swinging movement.

Other and further objects of the invention will more clearly appear from the description and claims hereinafter following.

In the drawings forming part of the specification, Figure 1 is a broken side elevational view of a railway car and winding mechanism, and disclosing the invention in connection therewith; Figure 2 is an enlarged end elevational view of the transmitting device forming the subject matter of the invention; and Figure 3 is a vertical sectional view of the invention, showing the device in

normal position in full lines, and at the limit of its swinging movement in dotted lines.

As shown in the drawings, a fragment of the end wall of the car is indicated at 10, and secured thereto is a winding mechanism, shown conventionally, and indicated by the reference character 11, the winding mechanism being adapted to take up and release the flexible means 12, shown in the form of a chain, the chain 12 having a horizontal portion 13 extending beneath the car and adapted to be connected with the brake shoes proper. The construction of the winding means is of a well known character and forms no part of the present invention except in so far as it enters into combination therewith.

In carrying out the invention, a supporting yoke 14 is secured to the under surface of the lower corner 15 of the car, the legs 16-16 of the yoke carrying a pivot pin 17 extending through the apex portion 18 of a generally segmental member or casting 19, the apex portion of the casting being provided with an integral sleeve 20 for the reception of the pivot pin 17. The segmental member is preferably formed with a pair of spaced walls 21-21, connected at one pair of side edges by means of a web 22 formed integrally with the sleeve 20, as shown. The opposite side edges of the member or casting are connected by a web 23 which extends from the sleeve 20 to a point somewhat short of the extremities of the casting, said web merging with an angularly disposed arcuate web 24, the latter forming the bottom of a groove defined by arcuate shoulders 25-25 formed integrally with the side walls 21-21 and with the web 24, the web 24 and shoulders 25 being cut out and terminating as indicated at 26.

An integral abutment 27 extends across the groove defined by the shoulders 25-25 and web 24, and at one side is curved, as indicated at 28, to conform to the curvature of one of the upright links 29 of the chain, as best shown in Figure 3. The opposite surface of the abutment 27 is beveled, as indicated at 30, to facilitate movement of the chain therewith when the chain is released.

The lower extremities of the walls 21-21 are connected by spaced arcuate webs 31-31,

these webs, along with the web 24 and shoulders 25—25, defining guide means which, with the side walls of the member, retain the chain 12 in position.

5 Rotatably mounted upon a pin 32 supported by the side walls 21—21 of the member 19, and arranged at one side of the center of said member, and between said side walls, is a sheave 33, having a grooved rim defined by 10 a web 34 and spaced flanges indicated at 35, the diameter of the sheave being such that the web 34 extends downwardly slightly beyond the web 24, as best shown in Figure 3. The groove of the sheave accommodates a 15 portion of the chain, as will be understood.

15 In operation, under the influence of gravity, and with the chain loose in the guides provided by the sheave 33, the web 24 and webs 31—31, the segmental member normally 20 hangs in depending position. Upon the initial take-up of the brake chain, the chain moves relatively to the segmental member without any effect thereon, but as soon as the chain becomes somewhat tightened, one of the 25 links of the chain will come into abutting relation with the abutment 27, causing the segmental member to move with the chain, and this movement may continue until just before the segmental member reaches the 30 dotted line position in Figure 3; upon reaching this position, the sheave 33 will have assumed such position that the chain will have left engagement with the abutment 27, and assumed such position as to bear solely upon 35 the sheave 33. The sheave being free to rotate, as much additional chain may be taken up as desired. When the brake is released, the segmental member will move with the chain until it reaches its depending position, 40 and the chain becoming loosened will move relatively to said member until the brake is entirely released.

It is particularly pointed out that unlimited take-up of the chain may be effected, the 45 device permitting relative movement of the chain with respect thereto during the initial take-up, and also permitting such movement during the final take-up, all to the end that difficulties resulting from variations in the 50 vertical and horizontal portions of the brake chain, due to wearing of the parts, will be obviated, and the construction afford great flexibility and efficiency.

While I have herein shown and described 55 what I now consider the preferred manner of carrying out my invention, the same is merely illustrative and I contemplate all changes and modifications that come within the scope of the claims appended hereto.

60 I claim:

1. In a brake mechanism of the character described, the combination with a winding member and flexible means having portions adapted to extend at angles to each other; 65 and a swingable device adapted to cooperate

with said flexible means adjacent the transition of the angular portions one into the other, said device having elements automatically engageable and disengageable with reference to said flexible means depending 70 upon the tension therein.

2. In a hand brake of the character described, the combination with a winding mechanism and a brake chain having portions adapted to extend at angles to each other; a swingable device adapted to cooperate with said chain adjacent the transition of the angular portions one into the other, said device having means for effecting movement of the same in unison with 75 said chain during one phase of operation, and permitting relative movement of said chain with reference to said device during another phase of operation.

3. In a hand brake for a railway car, the combination with winding means; of a flexible element cooperating with said winding means and having an angular portion extending beneath the car; and a device movably connected with said car and engaging 80 said flexible element, said device having means for automatically adjusting its position with reference to said flexible element, to compensate for variations in the length 85 thereof.

4. In a hand brake of the character described, the combination with a railway car having an end wall; of a winding device mounted upon said end wall; a flexible element extending from said winding device 100 to a point beneath the car; and a segmental member having its apex pivotally connected to the under-surface of said car adjacent the end wall, said member being provided with means engageable and detachable with reference to said flexible element, depending 105 upon the movement of the latter.

5. In a hand brake of the character described, the combination with a railway car having a winding device secured thereto and a flexible element having portions adapted to extend at an angle to each other; a swingable member secured to said car and interposed between the latter and said flexible element and having means engageable with 110 said flexible element for movement in unison therewith, said swingable member being restricted in its movement; and rotatable means carried by said swingable member and engageable with said flexible element 115 at the end of its movement to permit relative movement of said element with reference to said member.

6. In a hand brake of the character described, the combination with a winding mechanism and a brake chain having portions adapted to extend at angles to each other; a member movable about a fixed pivot and provided with a guide for said chain and an abutment, said chain being engage- 120

able with said abutment upon increase in tension therein and being detachable with respect to said abutment when said tension is decreased.

5 7. In a hand brake of the character described, the combination with a winding mechanism and a brake chain having portions adapted to extend at angles to each other; and a member movable about a fixed 10 pivot and provided with a guide for said chain and an abutment, said chain being engageable with said abutment upon increase in tension therein and being detachable with respect to said abutment when said tension 15 is decreased; and a sheave rotatably carried by said member and adapted to engage said chain when the latter is free of said abutment.

20 8. In a hand brake of the character described, the combination with a railway car having an end wall; of a winding mechanism mounted on said end wall; a chain extending from said winding element to a point beneath said car; a segmental member 25 having its apex pivotally connected to the undersurface of the car adjacent said end wall, said member comprising spaced walls between which is rotatably mounted a sheave, said member also being provided 30 with an abutment adjacent said sheave, the extremities of said walls being provided with webs cooperating with said sheave and abutment to loosely embrace said chain, said abutment and said sheave being arranged 35 to successively engage said chain to initially cause movement of said chain and member in unison and subsequently permit movement of said chain with reference to said member.

40 40. In witness that I claim the foregoing I have hereunto subscribed my name this 10th day of June, 1929.

ARTHUR F. O'CONNOR.
